HAND BAG-SEWING MACHINE

Giuseppe Renzo Cerioni, Milan, Italy, assignor to
 EL-CU-S. P. AZ. Eletro Cucitrice Industriale
 Portatile, Milan, Italy

Application March 3, 1950, Serial No. 147,515
 In Italy September 23, 1949

10 Claims. (Cl. 112—11)

1

My present invention relates to sewing machines of the type for closing, by sewing, the open mouth of a filled bag for carrying wheat or other material, or for joining, by sewing, cloth, fabric and canvas, or the like, the purpose being to improve the practicability of instruments of this kind, as well as to reduce their manufacturing cost, by the use of new and unique features made apparent throughout the specification.

The primary object of my present invention is to provide an electric-powered sewing machine of such external shape and such light and balanced weight that the same is easily carried by an operator in one of his hands and handled so as to follow the edges of the fabrics to be joined by sewing, irrespective of the inclination, direction, position and outline of such edges.

Another object of my present invention is to provide the machine with handling means and controlling devices so that the machine is easily controlled by the one hand of the operator which carries the same.

Another object of my present invention is to provide a mechanism to drive the several moving devices that start the formation of a "chain-type" seam and to move forth the joined edges of the bag-mouth, or the like, said mechanism to be easily enclosed in a casing shaped to produce the desired weight balance and practicability of the instrument.

Another object of my present invention is to provide a transmission device connecting the power source to the operating devices, so as to allow the operator to control the speed of same, letting the machine run slowly when engaging the parts to be sewed, and gradually speeding up when the sewing has started.

A still further object is to provide, in an electric-powered, hand, bag-sewing machine, a minimum of parts, high efficiency and a general arrangement which makes the device capable of hard and continuous work.

I attain the above said objects substantially by dividing the whole mechanism in two parts, or two groups of parts, one of which comprises the minimum of parts actuating the sewing operation and the movement of the sewed edges, and the second one of which comprises the driving electric motor, the transmission and the mechanism necessary to transform the continuous rotating movement of the motor driving shaft to produce reciprocating motion, properly timed, of the parts that finally provide the seam.

2

The first group of parts is enclosed in a very little head casing which is supported, by a couple of parallel bars, in an advanced position relative to a main casing, which encloses the second group of parts and comprises a "pistol-grip" handle. Enclosed in or connected to the rear end of the main casing is a small electric motor which drives the machine. In another embodiment of my invention, the power plant constitutes a separate unit from the hand-carried sewing machine, and the driving is made through a flexible shaft, which is joined to the rear end of the main casing. The whole machine looks substantially like a big pistol, in which the alignment of the head casing and main casing resemble the barrel, the head casing being similar to the muzzle.

The sewing and driving mechanism can be actuated according to any known system, provided that the chosen mechanism is divided as above said, according to the invention. The operating connection between the two groups of parts is performed by means of connecting rods or shafts passing through the bars joining the two casings. The rear face of the head casing acts as one of the two plates squeezing together the edges to be sewed, the second one being movably placed on the bars joining the two casings.

According to this disposition, the edges to be sewed are kept at right angle in relation to the alignment of two casings, and during the regular sewing of the mouth of a filled and upright bag, the instrument can be easily held by an operator, as easily as he can hold and horizontally aim a pistol. This feature gives the advantage that the weight of the whole apparatus is well balanced on the pistol-grip handle, and the little head casing can easily follow the outline of the parts to be sewed together.

The variability of the working speed can be accomplished by means of any known suitable mechanical transmission or by means of any known suitable electric device allowing gradual reduction of the current, A.C. or D.C., fed to the motor, the mechanical system being the preferred one.

In a preferred embodiment of my invention, the group of parts enclosed in the main casing (the group that, for simplicity, will be named the "driving group" through-out the remainder of this specification) comprises substantially one rotating disk-like member, the outline of which is shaped as a cam and gives axial reciprocating motion to a shaft the end of which carries the

feed dogs or toothed member for moving cloth placed between the two squeezing plates. On a face of said disk-like member is eccentrically placed a pivot which acts as a crank-shaft driving a connecting rod that gives the necessary reciprocating motion to the needle bar. On the other face of said member are two ring-like axial cams, one of which acts on the outer end of an arm carried by the abovesaid shaft, to which a reciprocating rotative motion is given, 10 that in turn moves the toothed member back and forth, the latter being connected to the same shaft by means of another arm. The second cam, by means of a second arm and a second shaft, gives reciprocating motion to the hook that in cooperation with the needle makes the chain type seam. Said hook is made according to any known system in the art of planning and constructing sewing machines. The hook, the toothed member and the arm connecting said member to its driving shaft are the movable parts enclosed in the head casing. The two shafts are enclosed in tubes connecting said casing to the main casing, and the latter encloses all remaining parts of the mechanism.

In a particularly preferred embodiment of my invention, the rotating disk-like member is driven by a helical gear meshing with a worm gear, the latter being driven by a transmission system comprising two staggered disks, facing each other, and an idle wheel squeezed therebetween, and means that allow the operator to vary the distance of the point of contact between the idle wheel and the faces of both disks so as to vary the transmission ratio between the first disk, driving the worm gear, and the second disk, directly coupled to the electric motor shaft.

In a preferred embodiment of my invention, the position of the idle wheel is varied by pressing on a trigger mounted in the pistol type handle, and said trigger is used to control a switch in the feeding circuit of the motor, the apparatus being arranged in such a manner that a little pressure exerted on the trigger closes the switch, causing a transmission on the lowest ratio position, while a gradual pushing on the trigger causes corresponding gradual movement of the idle wheel towards the highest transmission ratio position. On the left side of main casing, nearly over the pistol type handle, is placed a lever suitably connected to the movable counter-plate squeezing the edges to be sewed together against the rear face of the head casing. Such an embodiment allows the operator to handle and control the machine with one hand, which grips the handle, while the start, stop and speed control is effected by using the fore-finger and movement of the pressure foot is made by the thumb of the same hand.

In order to more fully describe this my invention reference will be made to the drawing accompanying and forming part of this specification, and wherein some parts of the machine are diagrammatically shown.

Referring to the drawings:

Fig. 1 is a perspective view of a machine according to my invention, as held by an operator, his right hand being illustrated with broken lines, while an open mouth of a filled bag is shown by dotted lines.

Fig. 2 is a diagrammatic, perspective view of the assembly of both the driving group and the group of parts producing the seam.

Fig. 3 is a diagrammatic and partially sec-

tioned, perspective view of one of the bars joining the two casings.

Fig. 4 is a diagrammatic, perspective view of the transmission connecting the constant speed power plant to the driving group.

Fig. 5 is a perspective view of a part of the mechanism of the present invention.

Fig. 6 is a perspective view of another part of the mechanism of the present invention.

Like numerals indicate like parts throughout the several views.

As shown in Fig. 1, the pistol-like general outline of the machine comprises various aligned parts; the small head casing 1 comprises, as its 15 rear face, a plate 2 against which the edges of the mouth 3 of a bag can be squeezed by a counter-plate 4 acting as a pressure foot and being axially movable along the tubes 5 and 6 extending from the front face 7 of the main casing 8 and firmly connecting casings 1 and 8 together. On the rear face of main casing 8 is mounted the casing 9 of a suitable lightweight electric motor.

This motor, if desired, can be separated from the machine, which then can be driven by any 25 suitable source of power through a flexible shaft, one end of which joins the machine on the same rear end of casing 8.

From the lower face of casing 8 a pistol type handle 10 extends, said handle 10 comprising a 30 trigger 11 easily operable by the forefinger of the hand which holds the handle and the thumb of the same hand easily acting on the flattened end of the lever 12 extending from the left side face of casing 8; said lever 12 is connected, by suitable means, to the movable counter-plate 4 so as to move said counter-plate from the plate 2, while when no action is exerted on said lever, said counterplate, being pushed by suitable springs is allowed to freely move against the 35 plate 2.

Fig. 5 discloses one possible linkage means for interconnecting the operating lever 12 and the pressure foot member 4 so that the latter may be moved against the action of springs 18 by operation of lever 12. As is shown in Fig. 5, the rod 60 is fixedly connected to the lever 12 and rotates about its own longitudinal axis upon operation of lever 12. Rod 60 has fixedly connected thereto a cam 61 which cooperates with the arm 62 of rod 63 which is connected at one end thereof to plate 4 so that when the outer operating end of lever 12, shown in Fig. 5, is moved downwardly the cam 61 will engage arm 62 to move the rod 63 and plate 4 against the action of springs 18.

From the front face 7 of casing 8 extends the front end of a bar 13, said front end being constructed to carry the needle 14, which operates through the plates 2 and 4, the latter being provided with suitable openings for this purpose.

On the upper face of casing 8 can be mounted a tension device 15 for the twine fed to the needle 14, as well as a feeding reel or bobbin, not shown, or any other suitable known device intended to carry and feed twine, or thread, or 60 sewing cotton, with which the seam is to be made.

The counter-plate 4 is firmly mounted on the front end of two tubular members 16 and 17, placed around and being slidable along the two tubes 5 and 6, respectively. Between the rear 70 end of said tubular members 16 and 17 and the front face 7 of casing 8 springs 18 are inserted (as shown in Fig. 3) so as to urge the counter-plate 4 against plate 2. Said springs 18 are enclosed by outer tubular members 19 and 20, also mounted on the front face 7 of casing 8, and

within which the rear parts of tubular members 16 and 17 are slidably enclosed.

The actuating mechanism enclosed by the above casings and parts is outlined in Fig. 2 and comprises a rotating disk-like member 21 connected with a helical gear 22 meshing with worm 23 borne by driving shaft 24. On the lower face of member 21 an eccentric pivot 70 extends down, as is clearly illustrated in Fig. 6 which shows disk 21 as viewed from the underside thereof, and said pivot and disk constitute a crank that reciprocates the needle bar 13 by means of a connecting rod, or link 25 pivotally connected at one end to bar 13 and at its opposite end to pivot 70. On the periphery of member 21 a cut-out 26 is formed, and said periphery acts as a cam cooperating with a roller 27 borne by the free end of an arm 28. Said free end bears another roller 29, arranged to run over outer part of the upper surface of member 21 and cooperating with a cam 30 mounted on the top surface of disk 21 and having the shape shown in Fig. 2.

On the same upper surface of member 21 runs along an inner circle of lesser diameter, a third roller 31 borne by the free end of a second arm 32, and along said inner circle the member 21 bears an annular cam 33, which covers the inner circle. The elements 30 and 33 act as axial cams relative to the rollers 29 and 31, respectively.

As consequence of this arrangement, the constant rotative motion of member 21 imparts to the arms 28 and 32 the following reciprocating and turning motions, timed with the reciprocating motion of needle 14: the arm 28 is moved up and down and moved back and forth, while the arm 32 only is moved up and down. Of course, the rollers 27, 29 and 31 are kept in contact with the respective cooperating cams by suitable spring devices, not shown. All the above described parts are enclosed in the main casing 8, and the described reciprocating motions are transmitted to the part enclosed in the head casing 1 by means of two shafts 34 and 35 firmly connected with arms 28 and 32, respectively, and moving inside the tubes 6 and 5, respectively. At their front ends, the shafts 34 and 35 bear, respectively, an arm 36 and a hook 37 that cooperates with the needle 14 to make a chain type seam, according to a well known system. The arm 36 is connected to and moves the plate 38, working in an opening of the plate 2 and provided with toothed surface 39 and a hollow 40 that allows the needle to enter in the head casing 1 and permit a loop of twine to be grabbed by the hook 37 to make a chain type seam. The shaft 35 imparts to the hook 37 the necessary reciprocating motion, while the shaft 34, with its double angular and axial reciprocating motions, imparts to the toothed plate 38, which acts as "feed dogs," the necessary transversal back and forth movements, and the necessary "setting back" during its return transversal movement.

As consequence of the above described division of mechanical parts of the whole work of the machine, the primary object of my invention is attained, because the reduced space required to enclose the small and lightweight parts 36, 37 and 38 allows the construction of a very little head casing 1 and the construction of a very well balanced and handy instrument.

An important improvement of the machine according to this invention is accomplished by inserting between the worm gear 22 and the electric motor or the driving flexible shaft, a transmission device as shown in Fig. 4. Such device

comprises two friction disks 41 and 42, respectively connected to the shaft 24 carrying worm 23 and to the shaft 43 of the motor, or coupled to the flexible driving shaft. Said disks 41 and 42 are parallel to and face each other, but are arranged in a suitable bearing frame (not shown) with the center of one disk substantially opposite the periphery of the second one.

Said disks 41 and 42 squeeze between themselves the idle wheel 44, the axis of which is perpendicular to the axis of both disks 41 and 42 and lies substantially in the same plane as the axes of rotation of the latter. Said idle wheel 44 is rotatably carried by a fork supporting member 45, pivoting around an axis 46 and provided with a tail 47 connected, by means of any suitable known mechanical transmission or linkage to the trigger 11. As is shown in Fig. 4, the trigger 11 is pivotally mounted by means of the shaft 50 connected thereto. To the trigger 11 there is connected the lever 51 having the inclined surface 52 which is maintained in engagement with the lower end of lever 47 by the spring 57 which bears against the lever 47 and urges the same towards the inclined surface 52. The spring 56 bears against the trigger 11 and urges the same in a direction opposite to the arrow 53. When the trigger is moved in the direction of arrow 53 against the action of spring 56, the inclined surface 52 is moved with respect to the lever 47 in the direction of arrow 54 so as to move lever 47 against the action of spring 57 in the direction of arrow 55 and in this way move the roller 44 nearer to the center of disk 41 so as to increase the speed of rotation of disk 41. When the trigger is released spring 56 moves it back to its original position, and spring 57 moves lever 47 back to its original position so as to thereby move roller 44 back to its original position over the center of disk 42. This arrangement allows the operator to run the machine at very slow speed while preparing the same for operation, and while engaging the parts to be sewed together, and allows the operator to gradually speed up the machine according to the difficulties of the sewing, and to obtain, at any instant, the best operation speed.

While I have described one form herein of my invention, I do not intend to limit myself thereby, it being apparent that several changes, modifications, additions and even omissions may suggest themselves to persons skilled in the art, and it being apparent that, without further analysis, the foregoing will so reveal the gist of my invention that others can, by applying current knowledge, readily adapt it for various applications without omitting features that, from the standpoint of the prior art, fairly constitute essential characteristics of the generic or specific aspect of this invention and, therefore, such adaptations should and are intended to be comprehended within the meaning and range of equivalence of the appended claims.

What I claim as new and desire to secure by Letters Patent is:

1. A sewing device, comprising in combination, a first casing having a side surface; sewing means located in said first casing; a second casing having a bottom surface and a side surface, said side surface of said second casing being located opposite to and facing said side surface of said first casing and said second casing being substantially larger than said first casing; elongated connecting means extending between said sides of said casings and interconnecting the same;

operating means partly mounted in said second casing, extending along said connecting means and cooperating with said sewing means in said first casing for operating the same; and handle means extending from and connected to a substantially central portion of said bottom surface of said second casing, whereby the sewing device may be easily supported and balanced by an operator holding said handle means and maintaining said connecting means in a substantially horizontal position.

2. A sewing device, comprising in combination, a first casing having a side surface; sewing means located in said first casing; a second casing having a bottom surface and a side surface, said side surface of said second casing being located opposite to and facing said side surface of said first casing and said second casing being substantially larger than said first casing; elongated connecting means extending between said sides of said casings and interconnecting the same; operating means partly mounted in said second casing, extending along said connecting means and cooperating with said sewing means in said first casing for operating the same; pressure foot means mounted about said connecting means; spring means operatively connected to said pressure foot means and urging the same toward said side surface of said first casing; and handle means extending from and connected to a substantially central portion of said bottom surface of said second casing, whereby the sewing device may be easily supported and balanced by an operator holding said handle means and maintaining said connecting means in a substantially horizontal position.

3. A sewing device, comprising in combination, a first casing having a side surface; sewing means located in said first casing; a second casing having a bottom surface and a side surface, said side surface of said second casing being located opposite to and facing said side surface of said first casing and said second casing being substantially larger than said first casing; rod means extending between said sides of said casings and interconnecting said casings; operating means mounted in said second casing, extending along said rod means and cooperating with said sewing means in said first casing for operating the same; pressure foot means mounted about said rod means; spring means operatively connected to said pressure foot means and urging the same toward said side surface of said first casing; moving means extending from said second casing and being operatively connected to said pressure foot means for moving the same against the action of said spring means away from said side surface of said first casing; and handle means extending from and connected to a substantially central portion of said bottom surface of said second casing, whereby the sewing device may be easily supported and balanced by an operator holding said handle means and maintaining said rod means in a substantially horizontal position, said handle means being located adjacent to said moving means.

4. A sewing device, comprising in combination, a first casing having a side surface; hook means mounted in said first casing for movement therein; serrated plate means for feeding material to be sewn, said plate means being mounted in said first casing for movement therein; a second casing having a bottom surface and a side surface, said side surface of said second casing being located opposite to and facing said side surface

of said first casing and said second casing being substantially larger than said first casing; a first rod extending between and passing transversely through said side surfaces of said casings, said first rod being fixedly connected adjacent one end thereof to said hook means; a second rod extending between and passing transversely through said side surfaces of said casing, said second rod being substantially parallel to said first rod and connected to said serrated plate means, elongated, needle-supporting bar means extending through said side surface of said second casing toward said side surface of said first casing, said bar means being substantially parallel to said rods and mounted in said second casing for reciprocal movement along the longitudinal axis thereof; operating means located in said second casing and being operatively connected to said first and second rods and said bar means for reciprocating the latter along its longitudinal axis, for oscillating said first rod about its longitudinal axis, for oscillating said second rod about its longitudinal axis and for reciprocating said second rod along its longitudinal axis; drive means operatively connected to said operating means for actuating the same; handle means extending from and connected to a substantially central portion of said bottom surface of said second casing; and control means operatively connected to said handle means and operating means for controlling the latter.

5. A sewing device, comprising in combination, a first casing having a side surface; hook means mounted in said first casing for movement therein; serrated plate means for feeding material to be sewn, said plate means being mounted in said first casing for movement therein; a second casing having a bottom surface and a side surface, said side surface of said second casing being located opposite to and facing said side surface of said first casing and said second casing being substantially larger than said first casing; a first rod extending between and passing transversely through said side surfaces of said casings, said first rod being fixedly connected adjacent one end thereof to said hook means; a second rod extending between and passing transversely through said side surfaces of said casing, said second rod being substantially parallel to said first rod and connected to said serrated plate means; at least one elongated tube extending between and being connected at its opposite ends to said side surfaces of said casings, respectively, so as to interconnect the same and so as to support said first casing from said second casing, said tube surrounding one of said rods; elongated, needle-supporting bar means extending through said side surface of said second casing toward said side surface of said first casing, said bar means being substantially parallel to said rods and mounted in said second casing for reciprocal movement along the longitudinal axis thereof; operating means located in said second casing and being operatively connected to said first and second rods and said bar means for reciprocating the latter along its longitudinal axis, or oscillating said first rod about its longitudinal axis, for oscillating said second rod about its longitudinal axis and for reciprocating said second rod along its longitudinal axis; drive means operatively connected to said operating means for actuating the same; handle means extending from and connected to a substantially central portion of said bottom surface of said second casing; and control means operatively

connected to said handle means and said operating means for controlling said operating means.

6. A sewing device, comprising in combination, a first casing having a side surface; hook means mounted in said first casing for movement therein; separated plate means for feeding material to be sewn, said plate means being mounted in said first casing for movement therein; a second casing having a bottom surface and a side surface, said side surface of said second casing being located opposite to and facing said side surface of said first casing and said second casing being substantially larger than said first casing; a first rod extending between and passing transversely through said side surface of said casings, said first rod being fixedly connected adjacent one end thereof to said hook means; a second rod extending between and passing transversely through said side surfaces of said casing, said second rod being substantially parallel to said first rod and connected to said serrated plate means; at least one elongated tube extending between and being connected at its opposite ends to said side surfaces of said casings, respectively, so as to interconnect the same and so as to support said first casing from said second casing, said tube surrounding one of said rods; pressure foot means mounted about said tube; spring means operatively connected to said pressure foot means for urging the same towards said side surface of said first casing, said spring means being located about said elongated tube; elongated, needle-supporting bar means extending through said side surface of said second casing toward said side surface of said first casing, said bar means being substantially parallel to said rods and mounted in said second casing for reciprocal movement along the longitudinal axis thereof; operating means located in said second casing and being operatively connected to said first and second rods and said bar means for reciprocating the latter along its longitudinal axis, for oscillating said first rod about its longitudinal axis, for oscillating said second rod about its longitudinal axis and for reciprocating said second rod along its longitudinal axis, said operating means comprising a first crank located in said second casing and being fixedly connected to said first rod, a second crank located in said second casing and being fixedly connected to said second rod, a rotatably mounted plate located in said second casing, and cam means mounted on one side of said rotatably mounted plate and cooperating with said first and second cranks for actuating the latter in a desired sequence so as to thereby oscillate said first and second rods about their longitudinal axes; drive means operatively connected to said rotatably mounted plate for rotating the same; handle means extending from and connected to a substantially central portion of said bottom surface of said second casing; and control means operatively connected to said handle means and said operating means for controlling the latter.

7. A sewing device, comprising in combination, a first casing having a side surface; hook means mounted in said first casing for movement therein; serrated plate means for feeding material to be sewn, said plate means being mounted in said first casing for movement therein; a second casing having a bottom surface and a side surface, said side surface of said second casing being located opposite to and facing said side surface of said first casing and said second casing being substantially larger than said first casing; a first rod extending between and passing transversely through said side surfaces of said casings, said first rod being fixedly connected adjacent one end thereof to said hook means; a second rod extending between and passing transversely through said side surfaces of said casing, said second rod being substantially parallel to said first rod and connected to said serrated plate means; elongated, needle-supporting bar means extending through said side surface of said second casing toward said side surface

of said first casing, said bar means being substantially parallel to said rods and mounted in said second casing for reciprocal movement along the longitudinal axis thereof; operating means located in said second casing and being operatively connected to said first and second rods and said bar means for reciprocating the latter along its longitudinal axis, for oscillating said first rod about its longitudinal axis, for oscillating said second rod about its longitudinal axis and for reciprocating said second rod along its longitudinal axis, said operating means comprising a first crank located in said second casing and being fixedly connected to said first rod, a second crank located in said second casing and being fixedly connected to said second rod, a rotatably mounted plate located in said second casing, and cam means mounted on one side of said rotatably mounted plate and cooperating with said first and second cranks for actuating the latter in a desired sequence so as to thereby oscillate said first and second rods about their longitudinal axes; drive means operatively connected to said rotatably mounted plate for rotating the same; handle means extending from and connected to a substantially central portion of said bottom surface of said second casing; and control means operatively connected to said handle means and said operating means for controlling the latter.

8. A sewing device, comprising in combination, a first casing having a side surface; hook means mounted in said first casing for movement therein; serrated plate means for feeding material to be sewn, said plate means being mounted in said first casing for movement therein; a second casing having a bottom surface and a side surface, said side surface of said second casing being located opposite to and facing said side surface of said first casing and said second casing being substantially larger than said first casing; a first rod extending between and passing transversely through said side surfaces of said casings, said first rod being fixedly connected adjacent one end thereof to said hook means; a second rod extending between and passing transversely through said side surfaces of said casing, said second rod being substantially parallel to said first rod and connected to said serrated plate means; elongated, needle-supporting bar means extending through said side surface of said second casing toward said side surface of said first casing, said bar means being substantially parallel to said rods and mounted in said second casing for reciprocal movement along the longitudinal axis thereof; operating means located in said second casing and being operatively connected to said first and second rods and said bar means for reciprocating the latter along its longitudinal axis, for oscillating said first rod about its longitudinal axis, for oscillating said second rod about its longitudinal axis and for reciprocating said second rod along its longitudinal axis, said operating means comprising a first crank located in said second casing and being fixedly connected to said first rod, a second crank located in said second casing and being fixedly connected to said second rod, a rotatably mounted plate located in said second casing, and cam means mounted on one side of said rotatably mounted plate and cooperating with said first and second cranks for actuating the latter in a desired sequence so as to thereby oscillate said first and second rods about their longitudinal axes, said rotatably mounted plate having peripheral portions which are located at

different distances from the center of rotation of said plate, pin means connected to said second crank and engaging said peripheral portions of said rotatably mounted plate so that the rotation of said plate moves said pin means to thereby reciprocate said second rod along its axis; drive means operatively connected to said rotatably mounted plate for rotating the same; handle means extending from and connected to a substantially central portion of said bottom surface of said second casing; and control means operatively connected to said handle means and said operating means for controlling the latter.

9. A sewing device, comprising in combination, a first casing having a side surface; hook means mounted in said first casing for movement therein; serrated plate means for feeding material to be sewn, said plate means being mounted in said first casing for movement therein; a second casing having a bottom surface and a side surface, said side surface of said second casing being located opposite to and facing said side surface of said first casing and said second casing being substantially larger than said first casing; a first rod extending between and passing transversely through said side surfaces of said casings, said first rod being fixedly connected adjacent one end thereof to said hook means; a second rod extending between and passing transversely through said side surfaces of said casing, said second rod being substantially parallel to said first rod and connected to said serrated plate means; elongated, needle-supporting bar means extending through said side surface of said second casing toward said side surface of said first casing, said bar means being substantially parallel to said rods and mounted in said second casing for reciprocal movement along the longitudinal axis thereof; operating means located in said second casing and being operatively connected to said first and second rods and said bar means for reciprocating the latter along its longitudinal axis, for oscillating said first rod about its longitudinal axis, for oscillating said second rod about its longitudinal axis and for reciprocating said second rod along its longitudinal axis, said operating means comprising a first crank located in said second casing and being fixedly connected to said first rod, a second crank located in said second casing and being fixedly connected to said second rod, a rotatably mounted plate located in said second casing, and cam means mounted on one side of said rotatably mounted plate and cooperating with said first and second cranks for actuating the latter in a desired sequence so as to thereby oscillate said first and second rods about their longitudinal axes, said rotatably mounted plate having peripheral portions which are located at different distances from the center of rotation of said plate. pin means connected to said second crank and engaging said peripheral portions of said rotatably mounted plate so that the rotation of said plate moves said pin means to thereby reciprocate said second rod along its axis, and an elongated link member pivotally connected adjacent one end thereof to said needle-supporting bar means and being pivotally connected adjacent an opposite end thereof to the side of rotatably mounted plate opposite to said one side thereof and at a point spaced from the center of rota-

tion of said plate so that the rotation of said plate reciprocates said bar means; drive means operatively connected to said rotatably mounted plate for rotating the same; handle means extending from and connected to a substantially central portion of said bottom surface of said second casing; and control means operatively connected to said handle means and said operating means for controlling the latter.

10. A sewing device, comprising in combination, a first casing having a side surface; hook means mounted in said first casing for movement therein; serrated plate means for feeding material to be sewn, said plate means being mounted in said first casing for movement therein; a second casing having a bottom surface and a side surface, said side surface of said second casing being located opposite to and facing said side surface of said first casing and said second casing being substantially larger than said first casing; a first rod extending between and passing transversely through said side surfaces of said casings, said first rod being fixedly connected adjacent one end thereof to said hook means; a second rod extending between and passing transversely through said side surfaces of said casing, said second rod being substantially parallel to said first rod and connected to said serrated plate means; elongated, needle-supporting bar means extending through said side surface of said second casing toward said side surface of said first casing, said bar means being substantially parallel to said rods and mounted in said second casing for reciprocal movement along the longitudinal axis thereof; operating means located in said second casing and being operatively connected to said first and second rods and said bar means for reciprocating the latter along its longitudinal axis, for oscillating said first rod about its longitudinal axis, for oscillating said second rod about its longitudinal axis and for reciprocating said second rod along its longitudinal axis; drive means operatively connected to said operating means for actuating the same, said drive means comprising a driving disc and a driven disc each having a side surface spaced from and facing the side surface of the other disc, the center of said driving disc being located opposite to the periphery of said driven disc, a roller member mounted between said side surfaces of said discs and having the periphery thereof in engagement with said side surfaces and linkage means operatively connected to said roller for locating the same at a desired position between the centers and peripheries of said discs so as to control the speed with which said driven disc is rotated by said driving disc; handle means extending from and connected to a substantially central portion of said bottom surface of said second casing; and control means operatively connected to said handle means and linkage means for operating the latter.
